UNITED STATES PATENT OFFICE.

JOSEPH KOON, OF NEW HAVEN, CONNECTICUT, ASSIGNOR TO LEWIS SCHIELE & COMPANY, OF NEW YORK, N. Y.

DESIGN FOR A CORSET.

SPECIFICATION forming part of Design No. 18,573, dated August 28, 1888.

Application filed July 16, 1888. Serial No. 280,100. Term of patent 14 years.

To all whom it may concern:

Be it known that I, JOSEPH KOON, of New Haven, in the county of New Haven and State of Connecticut, have invented a new Design 5 for Corsets; and I do hereby declare the following, when taken in connection with accompanying drawing and the letters of reference marked thereon, to be a full, clear, and exact description of the same, and which said drawing constitutes part of this specification, and represents a side view of a corset showing this design as embodied in the hip-section.

This invention relates to a design for the ornamentation of the side portion or hip-section 15 of a corset; and the design consists in the representation of a vertical central plain strip, combined with the representation of several series of solid ribs running from said central band forward and back, alternating with the 20 representation of lace-work, as shown in the accompanying illustration.

In the illustration, A represents the portion 25 of the corset at one side of the hip section—say, the rear—and B the portion of the corset, say, to the front of the hip-section, the hip section to which this design particularly relates

being between the said front and rear sections of the corset. On the face of the hip-section is the representation of a vertical central close or solid strip, C, and from each side of this 30 central strip is the representation of several series of solid ribs, D, as running forward from one edge of the central strip and rearward from the other edge, these said series of solid strips alternating with the representation of 35 lace-work E, as shown in the accompanying illustration.

I claim—

The herein-described design for a corset, consisting in the representation on the hip- 40 section of a vertical central strip, C, with the representation of several series of ribs, D, as running forward from one edge of said central strip and rearward from the opposite edge of the same strip, with the representation of 45 lace-work E between the representation of said several series of ribs D, and alternating therewith, as shown and described.

JOSEPH KOON.
